UNITED STATES PATENT OFFICE

155,298

DESIGN FOR A WHIPPING TOP

Palmerino La Falce, Buffalo, N. Y.

Application January 7, 1948, Serial No. 143,581

Term of patent 14 years

(Cl. D34—15)

To all whom it may concern:

Be it known that I, Palmerino La Falce, a citizen of the United States, residing at Buffalo, in the county of Erie, State of New York, have invented a new, original, and ornamental Design for a Whipping Top, of which the following is a specification, reference being had to the accompanying drawing, forming part thereof.

Figure 1 is a top plan view of a whipping top embodying my new design.

Figure 2 is an elevation thereof.

I claim:

The ornamental design for a whipping top, as shown.

PALMERINO LA FALCE.
